UNITED STATES PATENT OFFICE.

CHARLES L. SCHULTZ, OF WHEELING, WEST VIRGINIA.

STEAM-ENGINE.

No. 853,565.

Specification of Letters Patent.

Patented May 14, 1907.

Application filed July 11, 1906. Serial No. 325,648.

To all whom it may concern:

Be it known that I, CHARLES L. SCHULTZ, a citizen of the United States of America, and a resident of Wheeling, county of Ohio, and 5 State of West Virginia, have invented certain new and useful Improvements in Steam-Engines, of which the following is a specification.

My invention relates to new and useful improvements in steam engines, and more particularly to that class of steam engines having oppositely-reciprocating pistons; and it consists in the particular construction, arrangement and combination of parts which 15 will hereinafter be fully described.

The object of my invention is to provide a steam engine in which the steam is exhausted from one part of the cylinder to another after having been utilized to cause the outward 20 stroke of the pistons and is there utilized to assist in producing the return stroke thereof; or, in other words, to provide a steam engine in which the steam is twice utilized, and in which, consequently, an increase of power is 25 secured with a given volume of steam, or a given power is secured with a diminished volume of steam.

A further object of the invention is to provide a simple and novel device whereby the 30 admission of steam to the cylinder is automatically regulated and the ordinary steam chest is wholly dispensed with.

Further objects of the invention will be made apparent as further progress is made 35 in this specification.

In describing the invention in detail, reference is herein had to the accompanying drawings, forming a part of this specification, in which—

40 Figure 1 is a perspective view of the invention; Figs. 2 and 3 are vertical longitudinal sections of the same, respectively showing the pistons at the beginning and end of the outward stroke; Fig. 4 is a top plan view of the invention; Fig. 5 is a cross section on the line 5—5, Fig. 3; and Fig. 6 is a front elevation of the front piston.

Referring to said drawings, in which like reference - numerals designate like parts 45 throughout the several views—1 indicates the cylinder and 2 the steam-supply pipe leading directly thereto on one side midway between the ends thereof. In said cylinder are two oppositely-operating pistons 3 and 4 eccentrically mounted upon the ends of piston 55

rods 5 and 6 respectively, the piston rod 5 projecting from the piston 3 through the piston 4, as shown. Said piston rods 5 and 6 are projected through the rear end of the cylinder 1 and are respectively attached to 60 slides 7 and 8 which freely slide in a guide formed by parallel plates 9 and 10. The inner or front ends of said plates are bolted or otherwise rigidly secured to the rear face of the cylinder and are rigidly supported at 65 their rear ends by a stanchion 11 having arms 12 for securing it to an ordinary bed-plate. Said plates 9 and 10 are provided with longitudinal grooves 13 in their opposing faces in which travel corresponding tongues 14 provided on the ends of said slides 7 and 8. Pivotally attached to the rear edges of said slides 7 and 8 are pitmen 15 and 16 respectively for connecting said slides with ordinary oppositely-disposed cranks carried by 75 the driving shaft.

On the inner face of each piston at a point substantially registering with the entrance port of the steam-supply pipe 2, when said pistons occupy positions at the center of the 80 cylinder, is a small groove, said groove forming a passageway or entrance 17 between the pistons for the steam at the beginning of the outward stroke.

In the outer face of the piston 3 is a shallow socket which communicates at its inner end with the tapered end of a substantially conical opening leading through said piston from its inner face, said socket and opening forming an aperture 18 through said piston. 90 In said aperture is mounted a slideable pin 19 having a stem 20 and a tapered head 21, said head being adapted to seat in the conical opening and to serve as a valve for preventing the passage of steam when so seated from 95 the inner to the outer side of said piston. When the pin 19 is seated in said aperture, the stem 20 thereof projects outward beyond the face of the piston, as shown in Fig. 2. A cap 22 on the outer end of said stem prevents the dislodgment of said pin. In the outer face of said piston and communicating with the socket hereinbefore referred to is one or more shallow radiating grooves 23 which extend beyond the edge of the cap 22 100 to admit of the ready passage of steam through the aperture 18 when the pin is unseated, as shown in Fig. 3—that is, to admit of communication through the aperture without hindrance from said cap. The ob- 110

ject of the closable aperture in said piston will hereinafter be made apparent.

In the steam-supply pipe 2 is a valve 24 adapted to be manipulated to open and close communication between said pipe and the cylinder 1. As a means of automatically opening and closing said valve, I employ a simple valve-operating device which is indirectly connected with and operated by one of said pistons. Fixed upon the upper end of the valve-stem 25 is a lever 26 having a tapered point 27 and a rounded rear end 28. Extending parallel to the cylinder 1 and rigidly secured at its rear end to a post 29 which is mounted in the side of the slide 7 is a rod 30. Said rod lies contiguous to the point 27 of the lever 26 and is slidably mounted in the rear of its front end in a lug 31 which is attached to and projects from the front end of the cylinder, as shown. Adjustably mounted on said rod 30 at a suitable point is a collar 32 to which is attached one end of a rod 33 which projects forward to and engages the rounded rear end 28 of said lever. The point 34 of said rod 33 is curved substantially as shown in Figs. 1 and 4 and is adapted to push upon said lever to open the valve as said rod 30 begins to move forward at the beginning of the outward stroke of the pistons, thus admitting steam to the cylinder between said pistons. In the return stroke of said pistons, the point 34 of said rod 33 engages and pulls said lever back, closing the valve. A bent spring 35, suitably mounted, as shown, serves to normally hold said rod 33 in a position for engaging said lever, but admits of said rod being sprung back when the lever has been moved to its limit and to slide past said lever. Upon said rod 30 in front of the lever 26 is an adjustable collar 36 adapted to engage the point of said lever as it is turned forward by the rod 33, as hereinbefore described, to limit the forward turning movement of said lever. A similar adjustable collar 37 is provided on said rod 30 in the rear of said lever to engage the point of said lever and limit the rearward turning movement thereof when it is turned back by said rod 33.

Pivoted at right angles upon the extreme front end of the rod 30 which projects some distance beyond the front end of the cylinder is a rod 38, the front or free end of which is adapted for engaging the outer end of a slideable pin 39 which is mounted in the front end of said cylinder. Said pin 39 registers with, or, is in line with, the pin 19 and is adapted under certain conditions to engage therewith, as will be more fully explained herein-after. Said rod 38 rests upon and is supported in a substantially horizontal position by a stationary pin 40 which is mounted upon the front end of the cylinder and is inclined downward slightly, as shown. When resting upon the extreme front end of said pin 40, the

rod 38 stands with its free end directly behind the pin 39 and is adapted to force said pin 39 inward as it travels rearwardly with the rod 30 to which it is attached. As it travels rearwardly, the said rod 38 is gradually raised or elevated at its front end until it frees itself from engagement with said pin 39, being so elevated by the inclined pin 40 over which it slides in its travel.

The invention operates substantially as follows: Assuming all the parts to be properly adjusted and the pistons to occupy positions in the center of the cylinder, as shown in Fig. 2, steam is admitted past the valve 24, which is then partially open, through the steam-supply pipe 2 to the interior of the cylinder and between the opposing faces of the pistons through the passageway 17. There expanding, the steam forces said pistons in opposite directions, or toward the ends of the cylinder, communicating motion, through the intermediate mechanism hereinbefore described, to the main shaft, or driving shaft. As the piston 3 moves toward the front end of the cylinder, the rod 30, which is indirectly attached to said piston, moves forward therewith and, in so moving, the point 34 of the rod 33 engages and pushes upon the rear end of the lever 26, fully opening said valve 24. Simultaneously with the full opening of said valve, the point of said lever is engaged by the adjustable collar 37 and its turning movement is stopped thereby, and the point of the rod 33 slips by the rear end of said lever. Said collar 37, continuing to travel forward with the rod 30 to the end of the stroke, carries with it the point of the lever and completely closes said valve 24 at the end of the stroke. The slideable pin 19 in the piston 3 remains seated in the aperture 18 as the pistons are being forced outward, being held in that position by the pressure of the steam between the pistons. Just before the piston 3 reaches the limit of its outward stroke, the cap 22 of said slideable pin 19 strikes against the inner end of the slideable pin 39 and is thereby forced backward and unseated, permitting the steam to exhaust through the aperture 18 from between the pistons 3 and 4 to the end of the cylinder in front of said piston 3, where it, acting upon the outer face of said piston, exerts a small force which assists in forcing or driving said piston back on its return or inward stroke, the remainder of the power for said stroke being obtained from the momentum of the ordinary fly-wheel on the driving-shaft. After having been utilized in the end of the cylinder, the steam exhausts to the atmosphere through the exhaust pipe 42.

As the pistons move toward each other on the return or inward stroke, the rod 30 is moved rearwardly with the piston 3 to which, as before stated, it is indirectly attached. The valve 24, which has been closed at the

end of the outward stroke of the pistons, as hereinbefore described, remains closed until just before the pistons reach the limit of their inward movement, when the lever 26 is 5 engaged at its point by the collar 36 and is moved thereby to a position substantially at right angles to the cylinder, partially opening the valve for the admission of steam. Simultaneous with said partial opening of 10 the valve, the end 34 of the rod 33 slips back past the rear end of the lever to its original position, or the starting point.

When the rod 30 commences its return movement with the inward movement of the 15 pistons, the free end of the rod 38 engages the outer end of the slideable pin 39 and draws said pin inward therewith, said pin following directly behind the pin 19 in the piston 3, holding the aperture 18 open. The free end 20 of said rod 38 being supported in a substantially horizontal position by the inclined pin 40 is gradually raised as it travels backward until, at the end of the inward stroke of the 25 pistons, it releases said pin 39. The steam entering the cylinder immediately causes said pin 19 to seat itself in said aperture 18, and the seating of said pin thrusts the pin 39, which is in contact therewith, outward with considerable force. An arm 41 provided on 30 the rear side of the free end of said rod 38 serves as a stop for said pin 39 when it is thrust outward, as just mentioned. Said pin is thus prevented from passing outward a sufficient distance to interfere with the rod 38 assuming its proper position therebehind 35 when it moves forward with the outward stroke of the pistons.

43 indicates oil-cups located at suitable points in the device.

40 I have described my invention more or less in detail, but it is obvious that various slight changes may be made in the construction and arrangement of some of the parts composing the invention without departing 45 from the general spirit or scope thereof. Hence I do not wish to limit myself to the precise construction herein described.

Having thus described my invention, what I claim as new, and desire to secure by Letters Patent, is—

50 1. In a steam engine, the combination with a driving shaft having oppositely-disposed cranks, of a cylinder, oppositely reciprocating pistons in said cylinder, operative means connecting said pistons with said cranks, a steam-supply pipe opening into said cylinder midway between the ends thereof, a valve in said supply pipe, means operated by one of said pistons whereby said 55 valve is automatically manipulated to open and close communication between said supply pipe and said cylinder and also to regulate the admission of steam to said cylinder, and means in the foremost of said pistons, 60

automatically opened and closed respectively at predetermined points in the line of travel of said piston.

2. In a steam engine, the combination with a driving shaft having oppositely-disposed cranks, of a cylinder, oppositely reciprocating pistons in said cylinder, operative means connecting said pistons with said cranks, a steam-supply pipe opening into said cylinder midway between the ends 70 thereof, a valve in said supply pipe, means operated by one of said pistons whereby said valve is automatically manipulated to open and close communication between said supply pipe and said cylinder and also to regulate the admission of steam to said cylinder, a valve in the foremost of said pistons, and means whereby the last-mentioned valve is automatically opened at a predetermined point in the travel of said piston to allow the 80 steam behind said piston to exhaust to the opposite side thereof.

3. In a steam engine, the combination with a driving shaft having oppositely-disposed cranks, of a cylinder, oppositely reciprocating pistons in said cylinder, operative means connecting said pistons with said cranks, a steam-supply pipe opening into said cylinder midway between the ends 90 thereof, a valve in said supply pipe, means 95 operated by one of said pistons whereby said valve is automatically manipulated to open and close communication between said supply pipe and said cylinder and also to regulate the admission of steam to said cylinder, a valve in the foremost of said pistons, and means whereby the last-mentioned valve is automatically opened at or near the end of the outward stroke of said piston to allow the 100 steam behind said piston to exhaust to the opposite side thereof, and also whereby said valve is held open until said piston approaches the end of its inward stroke.

4. In a steam engine, the combination with a driving shaft having oppositely-disposed cranks, of a cylinder, oppositely reciprocating pistons in said cylinder, operative means connecting said pistons with said cranks, a steam-supply pipe opening into said cylinder midway between the ends 110 thereof, a valve in said supply pipe, means operated by one of said pistons whereby said valve is automatically manipulated to open and close communication between said supply pipe and said cylinder and also to regulate the admission of steam to said cylinder, and means for exhausting the steam which has been utilized between said pistons in producing the outward stroke thereof to the end 115 of the cylinder in front of the foremost piston 120 to be again utilized to assist in producing the return stroke thereof.

5. In a steam engine, the combination with a driving shaft having oppositely-disposed cranks, of a cylinder, oppositely reciprocating pistons in said cylinder, operative means connecting said pistons with said cranks, a steam-supply pipe opening into said cylinder midway between the ends 130 thereof, a valve in said supply pipe, means operated by one of said pistons whereby said valve is automatically manipulated to open and close communication between said supply pipe and said cylinder and also to regulate the admission of steam to said cylinder, and means whereby the last-mentioned valve is automatically opened at a predetermined point in the travel of said piston to allow the steam behind said piston to exhaust to the opposite side thereof.

roating pistons in said cylinder, operative connections between said pistons and said cranks, said connections consisting of piston rods attached to said pistons, one of said rods 5 projecting through and operating in the piston attached to the other rod, slides attached to said piston rods outside said cylinder, and pitmen pivotally attached at one end to said slides and at the other to said cranks, a 10 steam-supply pipe leading into said cylinder midway between the ends thereof to discharge steam between said pistons, a valve in said supply pipe, a lever fixed upon the stem of said valve, a rod connected at one end to 15 the slide which is operated by the foremost of said pistons, said rod extending forward parallel to said cylinder and contiguous to said lever and being slidably mounted at its front end, adjustable collars carried by said rod 20 for engaging the point of said lever at predetermined points in the travel of said rod to manipulate said valve, a second rod adjust-

ably mounted upon the first-mentioned rod, said second rod adapted for engaging the rear end of said lever at predetermined points in its travel to manipulate said lever, a valve in the foremost of said pistons, said valve adapted to be closed by the incoming steam from said supply pipe and to remain closed to or near to the end of the outward 25 stroke of said foremost piston, means for unseating said valve at or near the end of said stroke to allow steam behind said piston to exhaust to the end of the cylinder in front of said piston, and means for holding said valve 30 unseated to or near to the end of the inward stroke of said piston.
